UNITED STATES PATENT OFFICE.

CLARENCE E. LOMAX, OF CHICAGO, ILLINOIS, ASSIGNOR, BY MESNE ASSIGNMENTS, TO AUTOMATIC ELECTRIC INC., OF CHICAGO, ILLINOIS, A CORPORATION OF DELAWARE.

AUTOMATIC TELEPHONE SYSTEM.

Application filed August 5, 1925. Serial No. 48,371.

This invention relates to automatic telephone systems in general, but is more particularly concerned with telephone systems in which primary line switches, or forward hunting switches, are used in combination with secondary finder switches, or backward hunting switches, to connect a calling subscriber's line with a trunk to an idle succeeding switch; and the object of this invention, broadly stated, is the provision of a new and improved trunking scheme for associating the primary line switches and the secondary finder switches.

This object and novel features relating to circuit details and other features not specifically mentioned will be described fully in the following specification, reference being had to the accompanying drawings comprising Figs. 1 and 2. Fig. 1 is a schematic 10 trunking diagram illustrating the particular method of trunking between the primary line switches and the secondary finder switches disclosed in this invention. Fig. 2 shows by means of the usual circuit diagrams a sufficient amount of the apparatus indicated in Fig. 1 for a clear understanding of the operation of the system.

The trunking diagram shown in Fig. 1 will be first briefly explained. In this diagram is shown, in simple form, the trunking arrangement between the local subscribers' lines, the individual primary line switches, the secondary finder switches, and the first selector switches. In the particular lay-out shown, the subscribers' lines such as A, are divided into groups of 100 lines, each line being connected to an individual primary line switch, such as C. The line switches of each group have their banks multiplied together, and have access to ten outgoing trunks. The selection of an idle trunk is governed by a master switch, such as MS, one master switch being individual to each group of primary line switches.

The secondary finder switches are also divided into groups, the switches of each group having their banks multiplied together. The number of finder switches in each group is variable depending on traffic conditions. Permanently connected to each finder switch is a first selector, such as E. In the lay-out illustrated, it is assumed that ten trunks from each of 25 groups of primary line switches, only the first three groups of which

are shown, terminate in the banks of ten groups of secondary finder switches, only the first three of the latter being shown. Each trunk in a particular group of primary line switches terminates in the banks of a different group of secondary finder switches. It is further assumed that the banks of the finder switches contain 25 sets of contacts. With this arrangement, then, there will be one trunk from each primary line switch group terminating in each of the ten secondary finder switch groups. In a practical case this particular arrangement as regards the number of trunks per group or the number of groups cannot always be carried out. In any event, each primary line switch group will have one or more trunks terminating in each secondary finder switch group. Such deviations from the special case as illustrated are not departures, however, from the general trunking scheme as outlined.

A distributor switch, such as D, is individual to each group of secondary finder switches. By means of a separate start wire connected to each of the 25 trunks terminating in the banks of the associated group of secondary finder switches, the distributor, having preselected an idle finder switch, starts the selected idle finder switch to find the calling trunk.

The apparatus shown by means of the usual circuit diagrams in Fig. 2, may now be briefly described. Substation A is an ordinary automatic telephone substation having the usual talking instrumentalities and a calling device for controlling the operation of the automatic switches. The line conductors terminate at the exchange in the individual primary line switch C, which is of the well known plunger type, modified in circuit arrangements, however, as will be described in detail in connection with its operation.

The master switch MS, indicated merely by a dotted rectangle, may be of the type shown and described in the U. S. patent to Newforth No. 13,901, reissued April 13, 1915, modified to include a supervisory relay such as relay 204 for an alarm circuit.

The distributor D is a non-numerical switch mechanically of the well known rotary type whose wipers have no normal position and move in a forward direction only. When a certain trunk is seized by a primary

line switch, the distributor switch associated with the group of finder switches in whose banks the seized trunk terminates, starts a preselected idle finder switch by means of a start wire connected to the seized trunk to hunt for the seized trunk, after which it rotates its wipers to preselect the next idle finder switch in preparation for another call.

The secondary finder switch F is also a non-numerical switch mechanically of the well known rotary type whose wipers have no normal position and move in a forward direction only. Its function is to hunt for the trunk seized by a primary line switch, and when found, to connect the seized trunk to selector E and disconnect the hunting mechanism therefrom.

The first selector E, of which only the essential parts having to do with the operation of finder switch F are shown, is of the well known Strowger vertical and rotary type.

The trunk designated X in Fig. 1, accessible to the lineswitches of lineswitch group 1, such as lineswitch C, and terminating in the banks of finder-switch group 1 containing finder switch F, is the trunk shown in Fig. 2, extending from bank contacts 41-44, inclusive, to bank contacts 45-48, inclusive. The trunk designated Y in Fig. 1, accessible to the lineswitch of lineswitch group 2, such as lineswitch C', and terminating in the banks of finder-switch group 1, is the trunk shown in Fig. 2 extending from bank contacts 41'-44', inclusive, to bank contacts 45'-48', inclusive.

Having briefly explained the object of the invention and the apparatus involved in carrying it out, the operation of the equipment will now be explained more in detail. For this purpose it will be assumed that the subscriber at substation A desires to obtain connection with some other subscriber in the exchange. When the subscriber at substation A removes his receiver to initiate a call, a direct current bridge is placed across the line conductors 11 and 12. A circuit is thereby closed for the line relay 14 which may be traced from ground at springs 23, line conductor 11, the bridge at the substation A, line conductor 12, springs 24, through the winding of the line relay 14, conductor 201, through the winding of the supervisory relay 204, included with the master switch equipment, to battery. Line relay 14 operates and closes a locking circuit for itself at armature 21; prepares a starting circuit by placing ground on the spring 33 at armature 22; prepares an unlocking circuit at armature 20; and closes a circuit for the pull down winding 15, which may be traced from ground by way of the working contact and armature 19, through the pull down winding 15, conductor 202 to the open-main battery supplied from the master switch. The supervisory relay 204 operates and closes a

circuit for an alarm circuit (not shown) at armature 205. This alarm circuit may be any of the well known types which give an alarm after the circuit is maintained closed for a period longer than the normal period that relay 204 should be in operation. The pull down winding 15 energizes and operates both the plunger arm 17 and the cut-off armature 16; the former, through the medium of its plunger (not shown), forces the bank springs 31-34, inclusive, into engagement with the contacts 41-44, inclusive, respectively, it being assumed that the plungers of this group of lineswitches including lineswitch C are standing opposite the trunk accessible at bank contacts 41-44, inclusive; and the latter disconnects the line conductors 11 and 12 from the normal ground connection and from the upper terminal of the line relay 14, respectively. The private normal conductor 13 which is connected to the test contacts in the connector banks is placed sufficiently below battery potential from ground by way of working contact and armature 21 and through the winding of line relay 14 to guard the line to substation A from being seized by a connector at this time. A circuit is also closed for the cut-off winding 16 from ground by way of the working contact and armature 21, through the winding of the line relay 14, working contact and armature 20, through the cut-off winding 16 to battery.

As a result of the engagement of contacts 31-34, inclusive, with contacts 41-44, inclusive, respectively, the talking loop is extended to the finder switch F; ground potential is placed on the finder switch bank contact 47, and on the start conductor 76, thereby closing a circuit through the winding of the start relay 77 to battery; and by reason of the ground by way of the working contact and armature 21, through the winding of line relay 14, working contact and armature 20, bank contact 32, bank contact 42, conductor 203, a potential sufficiently below battery potential is placed on the master switch bank contact to which conductor 203 is connected to operate the master switch MS in the well known manner. The plungers of all the remaining idle line switches controlled by the master switch MS are then advanced into position before the terminals of the next idle trunk. It may be mentioned that during the operation of the master switch, the open-main battery is disconnected from the conductor 202 thereby opening the circuit for the pull down winding 15. The cut-off winding 16 is energized sufficiently over the previously traced circuit to hold both the plunger arm 17 and the cut-off armature 18 in an operative position. Start relay 77 operates and places ground on the start conductor 80 at armature 81 and the working contact. It is assumed that

finder switch F is idle at this time and that the wipers 73 and 74 of the distributor switch D are in engagement with bank contacts 71 and 72, respectively. If the finder switch wipers 51-54, inclusive, happen to be standing on the bank contacts 45-48, inclusive, when the trunk terminating in such bank contacts is seized, the switching relay 61 will energize immediately.

10 It is assumed, however, that the wipers 51-54, inclusive, are standing on a set of bank contacts other than bank contacts 45-48, inclusive. A circuit may then be traced from ground on the conductor 80, 15 the resting contact and armature 79, wiper 74, bank contact 72, the resting contact and armature 68, interrupter springs 63, through the winding of the stepping magnet 62 to battery. Stepping magnet 62 energizes and 20 opens its own circuit at the interrupter springs 63. Stepping magnet 62 deenergizes and upon releasing its armature moves the wipers 51-54, inclusive, one step, and again closes its own circuit at the interrupter 25 springs 63. Stepping magnet 62 operates a second time, opens its own circuit at interrupter springs 63, and in deenergizing moves its switch wipers 51-54, inclusive, another step. This action continues until the wipers 30 51-54, inclusive, are moved so that wiper 53 comes into engagement with a grounded contact indicating that the wipers 51-54, inclusive, have found a calling trunk. If this happens to be some trunk terminating in 35 bank contacts accessible to the wipers 51-54, inclusive, before the trunk terminating in the bank contacts 45-48, inclusive, for example, the trunk terminating in bank contacts 45'-48', inclusive, the wipers 51-54, inclusive will be arrested on bank contacts 45'-48', inclusive, and proceed to extend that connection. The calling trunk terminating in bank contacts 45-48, inclusive, will then be found by the next idle finder 40 switch as will be understood from subsequent descriptions. It will be assumed, however, that the trunk seized by the line switch C terminating in the bank contacts 45-48, inclusive, is the first calling trunk appearing in the finder switch banks. A circuit may 45 now be traced for the switching relay 61 of the finder switch F from ground by way of the bank contact 47 engaged by wiper 53, through the upper winding of the switching 50 relay 61 to battery. Switching relay 61 energizes and closes a point in the chain circuit to be described later, at armature 64; extends the talking loop by way of armatures 65 and 69 and their working contacts, armatures 106 and 109 and their resting contacts, to the upper and lower windings of the line 55 relay 101 of the selector D to battery and ground; opens the circuit of the stepping magnet 62 at armature 68; prepares a circuit 60 for the stepping magnet 75 at armature 67;

and places direct ground potential on the private normal conductor 13 by way of the working contact and armature 66, wiper 52, bank contact 46, bank contact 42, and spring 32, thereby also fully energizing the cut-off 70 winding 16 and short circuiting the line relay 14. Line relay 14 deenergizes and opens the circuit for the pull down winding 15 at armature 19; removes ground potential from bank contact 47 and the start conductor 76 at 75 armature 22, thereby opening the initial energizing circuit for the upper winding of the switching relay 61 and the circuit for the start relay 77; opens the initial circuit for energizing the cut-off winding 16 and for 80 placing the initial guarding potential on the private normal conductor 13 at armature 20; and opens its own locking circuit which includes the winding of the supervisory relay 204, at armature 21. 85

If the line relay failed to be unlocked for any reason, such as the failure of the finder switch to operate properly and feed back ground, the supervisory relay 204 would also be held operated and an alarm would be given, as described previously. Line relay 14 is given a slow-acting characteristic when its winding is short circuited and does not remove ground from contact 47 to open the initial energizing circuit of switching relay 95 61 until sufficient time has elapsed for the holding circuits for the lower winding of switching relay 61 to be closed, which will be described subsequently. 100

The line relay 101 of the selector D energizes over the previously traced circuit including the talking loop and operates to close a circuit for the release relay 102 at its armature 104. Release relay 102 operates and places ground potential on the holding conductor 100 at armature 105 and the working contact. Ground on the holding conductor 100 closes the holding circuit for the lower winding of the switching relay 61 and also closes the circuit for the stepping magnet 75 110 105 by way of the working contact and armature 67, bank contact 71, wiper 73, interrupter springs 86, through the winding of the stepping magnet 75, armature 84 and the resting contact, to battery. The slow acting relay 70 is also operated in multiple with the stepping magnet 75 over an obvious circuit. 115

Motor magnet 75 operates and opens its own circuit at interrupter springs 86. In releasing, motor magnet 75 moves the distributor switch wipers 73 and 74 into engagement with bank contacts 71' and 72', associated with the next finder switch. If this finder switch is busy, ground will be present on bank contact 71', being fed back over the holding conductor of the corresponding selector. A circuit will therefore again be closed for motor magnet 75. Motor magnet 75 will energize, open its own circuit at interrupter springs 86, and in de- 120 125 130

energizing, will move the distributor switch wipers 73 and 74 another step. This action will continue until the wipers 73 and 74 are resting on the bank contacts to which the controlling conductors of an idle finder switch are connected. The distributor switch D is then in readiness to start this idle finder switch when another call is initiated over a trunk extending to this particular finder switch group. Ground is maintained on contact 71 to prevent the distributor wipers from becoming engaged with contacts 71 and 72, during the time that the finder switch F is associated with the present connection.

The slow-acting relay 70 is energized in multiple with the stepping magnet 75 and is maintained energized during the entire hunting operation of the stepping magnet. Being slow-acting, relay 70 remains operated for an interval after the wiper 73 stops on a contact representing an idle finder switch and maintains the starting conductor 80 disconnected from the wiper 74 at its armature 79 during this time. Start relay 77 deenergizes when ground is removed from start conductor 76 and removes ground from the start conductor 80 at armature 81 before the slow-acting relay 70 has had time to deenergize and again connect start conductor 80 to the distributor wiper 74. The function of the slow acting relay 70 is to keep the start conductor 80 disconnected from the wiper 74 for an interval long enough to allow the line relay 14 to deenergize, and the start relay 77 to deenergize and remove ground from the start conductor 80. If this circuit were not held open during this time and the distributor D immediately found an idle finder switch, this idle finder switch might be uselessly operated before the start relay 77 deenergized and removed ground from the conductor 80 at armature 81.

The operation of the selector E is well known to those skilled in the art. It will therefore suffice to mention that the selector E operates in response to the first digit dialled by the subscriber at substation A to raise its wipers opposite the level of bank contacts corresponding to the digit dialled and then automatically rotates its wipers in search for an idle trunk to a succeeding switch. When an idle trunk is found, the switching relay of the selector E, indicated in the drawings by the rectangle 103, operates and disconnects the line relay 101 and extends the talking loop by way of armatures 106 and 109 and the working contacts, wipers 111 and 113, bank contacts 121 and 123 to the line relay of the succeeding switch, similar to line relay 101. The holding conductor is also extended to the succeeding switch at armature 107, and a release circuit (not shown) connected to the

resting contact of armature 104 is held open at armature 108. The line relay of the succeeding switch operates and closes a circuit for the release relay of that switch similar to release relay 102. The release relay 70 operates and places ground on its release conductor which is fed back by way of bank contact 122, wiper 112, armature 107 and the working contact before the release relay 102, whose circuit was opened when line relay 101 deenergized, has had time to fall back. Consequently there will be no interruption of ground on the holding conductor 100. The switching relay 103 is also maintained operated from ground on conductor 80.

The connection is extended in this manner through one or more other selectors, depending on the size of the telephone system, each being responsive to a digit dialled 85 by a subscriber at the calling substation A, to a connector in whose banks the line of the calling substation terminates. The connector operates in response to the last two digits dialled by the subscriber at substation A, raises its wipers and rotates them into engagement with the set of bank contacts at which the line of the called substation terminates, causes the substation to be signalled, and finally completes the talking connection between the calling subscriber at substation A and the called substation when the subscriber at the called substation removes his receiver.

The two subscribers may now hold conversation. After the conversation is terminated, both subscribers will replace their receivers on their respective switch hooks. These operations by the calling and called subscribers cause the release of the connector 105 switch in the well known manner. The release of the connector removes ground from the holding conductors extending through the selectors, including the holding conductor 100. Removing ground from the holding conductors of the selector switches associated with the connection causes the deenergization of the switching relays of the selectors. Release circuits for the various selectors are closed by armatures, such as armature 108, and their respective resting contacts, to restore the selectors to normal. Removal of ground from the holding conductor 100 opens the circuit for the lower winding of the switching relay 61. Switching relay 61 thereupon deenergizes and restores its armatures back to normal. The circuit of the cut-off winding 16 is opened at armature 66 which thereupon also deenergizes. The plunger of arm 17 and the cut-off armature 18 are then released. It may be stated at this time that it is assumed that the line switches, such as C, are equipped with self restoring plungers; that is, as soon as a plunger arm is released, it 130

is forced back into engagement with the shaft by the action of a spring and its position with respect to idle trunks is again under the control of the master switch. 5 With this arrangement all the plungers of the idle line switches are always standing opposite the same idle trunk. Line switch C is now in position to extend another call when one is again initiated by the subscriber 10 at substation A. By the removal of ground from holding conductor 100, ground is also removed from the distributor bank contact 71. With the release of the switching relay 61, the finder switch F is again in position 15 ready to be selected to extend another call. The finder switch F, however, will not be selected until the wipers of the distributor D are again rotated into engagement with the bank contacts 71 and 72. 20 The function of the chain relay 78 and the circuits associated therewith will now be described. It is evident to those skilled in the art that traffic conditions never demand that there be as many finder switches in a 25 group as there are incoming trunks terminating in the banks of that group. Therefore, if no means were taken to prevent it, a call might be extended over a trunk terminating in a group of finder switches when 30 all the finder switches of that group were busy which ordinarily would result in the failure of the connection. A chain relay 78 whose circuit includes an armature and a working contact on the switching relay 35 of all the finder switches of a group is provided for each group. The rectangle labeled 61' represents the switching relay similar to switching relay 61 of the first finder switch in the same group containing finder 40 switch F. The working contact of the armature 64' included in the chain circuit is grounded. When all the finder switches of a group are busy, all the switching relays similar to and including switching relay 61 45 will be energized. The chain circuit will be completed, extending from ground on the working contact and armature 64' through the corresponding working contacts and armatures of the other busy finder switches, armature 64 and the working contact, through 50 the winding of the chain relay 78 to battery. The armature 83 of the chain relay 78 is a specially constructed armature having 25 working contacts. The release conductor of 55 each trunk terminating in the banks of the group of finder switches containing finder switch F is connected to one of these working contacts. The chain relay 78 operates over the previously traced circuit, and places 60 ground on the release conductor of each of the 25 trunks terminating in the banks of this group of finder switches, thereby marking 65 all these trunks engaged, even though some of them are not being used in an actual connection. The release conductors of the 70 trunks are connected to contacts in the various master switch banks. In this particular case, each of the 25 release conductors are connected to a contact in a different master switch bank, there being 25 master switches, 70 one for each group of line switches. If the plungers of the line switches of any of the groups of line switches are positioned before a trunk leading to this particular group of 75 finder switches, the master switch controlling this group of line switches will immediately be operated to move the plungers of the line switches opposite a trunk extending to some other group of finder switches. As a result, the plungers of no line switches 80 of any group will be standing opposite a trunk leading to this group of finder switches, and consequently no more calls will be trunked to this particular group of finder 85 switches.

As soon as one of the finder switches of this group becomes idle, the chain circuit will be opened at the armature of the idle finder switch corresponding to armature 64 and the chain relay 78 will be deenergized. 90 The guarding ground placed on the release conductors of the trunks will then be removed at armature 83. Another call may now be extended over any one of the remaining idle trunks terminating in this group 95 of finder switches.

Chain relay 78 has an additional function in that it removes battery from one terminal of the stepping magnet 75 at armature 84 when all the finder switches of the 100 group are busy, thereby preventing useless rotation of the distributor wipers 73 and 74 in search for an idle finder when all the 105 finder switches are busy.

In Fig. 2 is shown the test jack 110 having one of the terminals connected to bank contact 71 and the other of the terminals grounded. This test jack may be at any convenient place, its purpose being to manually 110 busy-guard the finder F and the associated selector E against being selected to extend a connection for any reason that might occur. By connecting the two terminals of the test jack 110, ground is placed on the corresponding contact in the distributor switch bank, 115 thereby preventing the distributor D from selecting the finder switch F.

Should a call be extended to the substation A by some other subscriber in the exchange, the cut-off winding 16 is energized 120 from ground on the private normal conductor 13. Private normal conductor 13 is grounded in the well known manner by the connector which has been selected by the calling subscriber. The magnetism produced by the energization of the cut-off winding 16 is not sufficient to actuate the plunger arm 17, but operates the cut-off armature 18 to disconnect the line conductors 11 and 12 from their normal connec- 125 130

- tions to ground and the upper terminal of line relay 14 by separating springs 23 and 24, respectively. When the subscriber at substation A removes his receiver in response to the ringing of the bells at his substation, the direct current bridge is closed across the line conductors 11 and 12 which operates relays in the connector in the well known manner to complete the talking connection.
- 10 Having fully described the operation and novel features of this invention, what is considered new and is desired to have protected by Letters Patent will be pointed out in the appended claims.
- 15 What is claimed is:
1. In a telephone system, a group of line switches, a plurality of groups of finder switches, a group of trunks accessible to said line switches each trunk terminating in a different group of finder switches, means for automatically operating any line switch to seize an idle trunk, and means for starting an idle finder switch of the group in which the seized trunk terminates to find the seized trunk.
  2. In a telephone system, a plurality of groups of line switches, a plurality of groups of finder switches, outgoing trunks from each group of line switches, each group of line switches having a trunk terminating in each group of finder switches and each group of finder switches terminating a trunk from each group of line switches, means for operating a line switch to seize an idle trunk accessible thereto, and means for starting an idle finder switch of the group in which the seized trunk terminates to find the seized trunk.
  3. In a telephone system, a plurality of groups of line switches, a plurality of groups of finder switches, each group of finder switches containing a less number of finder switches than the number of groups of line switches, outgoing trunks from each group of line switches, each group of line switches having a trunk terminating in each group of finder switches and each group of finder switches terminating a trunk from each group of line switches, means for operating a line switch to seize an idle trunk accessible thereto, means for starting an idle finder switch of the group in which the seized trunk terminates to find the seized trunk, and means for preventing the seizure of an idle trunk which terminates in a group of finder switches when all the finder switches of that group are busy.
  4. In a telephone system, a plurality of groups of line switches, a plurality of groups of finder switches, a group of trunks from each group of line switches, each group including a trunk terminating in each group of finder switches, a starting relay individual to each trunk, means for operating a line switch to seize an idle trunk accessible there-

to, and means for operating said start relay individual to the seized trunk to operate an idle finder switch of the group in which the seized trunk terminates to find the seized trunk.

5. In a telephone system, a plurality of groups of line switches, a group of finder switches, a trunk from each group of line switches terminating in the banks of said group of finder switches, a relay individual to each of said trunks, means for operating any line switch to seize the trunk accessible to it terminating in said group of finder switches, and means for energizing the relay individual to the trunk seized to start an idle finder switch of the group to hunt for the seized trunk.

6. In a telephone system, a plurality of groups of line switches, a group of finder switches containing a less number of finder switches than the number of groups of line switches, a trunk from each group of line switches terminating in the banks of said group of finder switches, a relay individual to each of said trunks, means for operating any line switch to seize the trunk accessible to it terminating in said group of finder switches, means for energizing the relay individual to the trunk seized to start an idle finder switch of the group to hunt for the seized trunk, and means for incapacitating said first means when all the finder switches are in use.

7. In a telephone system, an individual line switch, a line relay in said switch having a winding, subscriber controlled means for energizing said winding to initially operate said relay, means for operating said line switch responsive to the operating of said relay, means for maintaining said winding energized independent of said subscriber, and means for automatically short circuiting said winding after the completion of the operation of said lineswitch.

8. In a telephone system, an individual line switch, a line relay in said switch having a winding, subscriber controlled means for energizing said winding to initially operate said relay, means for operating said line switch responsive to the operation of said relay, means for maintaining said winding energized independent of said subscriber, a succeeding switch, means for operating said succeeding switch in response to the operation of said line switch, and means for de-energizing said winding upon the completion of the operation of said succeeding switch.

9. In a telephone system, a subscriber's line, a line switch individual to said line, a relay in said switch having a winding, subscriber controlled means for energizing said winding to initially operate said relay, means for placing a guarding potential on a conductor of said line upon the energization of said relay, and means for maintaining said

winding energized independent of said subscriber.

10. In a telephone system, a subscriber's line, a line switch individual to said line, a relay in said switch having a winding, subscriber controlled means for energizing said winding to initially operate said relay, means for placing a guarding potential on a conductor of said line upon the energization of said relay, means for maintaining said winding energized independent of said subscriber, a succeeding switch, means for operating said succeeding switch in response to the operation of said line switch, and means for deenergizing said winding upon the completion of the operation of said succeeding switch without removing said guarding potential from said conductor.

11. In a telephone system, a group of line-
20 switches, a plurality of groups of finder switches, a group of trunks accessible to said lineswitches, each trunk terminating in a different group of finder switches, means for operating any lineswitch to seize an idle
25 trunk, and means common to the finder group in which said seized trunk terminates and individually associated with an idle finder switch of that group for starting that finder to find said seized trunks.

30 12. In a telephone system, a plurality of groups of lineswitches, a plurality of groups of finder switches each group of finder switches containing a less number of finder switches than the number of groups of lineswitches, outgoing trunks from each group of lineswitches, each group of lineswitches having a trunk terminating in each group of finder switches and each group of finder switches terminating a trunk from each
35 group of lineswitches, a distributor switch for each finder switch group including means for preselecting idle switches of that group, means for operating a lineswitch to seize an idle trunk accessible thereto, means respons-
40 sive thereto for starting a preselected idle finder of the group in which the seized trunk terminates to find the seized trunk, and means for disabling the distributor of and for preventing the seizure of an idle trunk
45 which terminates in a group of finder switches when all the finder switches of that group are busy.

50 13. In a telephone system, a subscriber's line terminating in an individual lineswitch, a group of finder switches, a distributor including means for preselecting an idle one of said finders, a trunk line outgoing from said lineswitch and terminating in the banks of said finder switches, means on said sub-
55 scribe's line for operating said lineswitch to seize said trunk, and means associated with said trunk and distributor for extending a

start circuit only if said distributor has pre-selected an idle finder.

65 14. In a telephone system, a plurality of groups of lineswitches, a plurality of groups of finder switches, trunks outgoing from said lineswitches and terminating in said finder switches, a distributor switch for each 70 finder group including means for preselecting idle finders of that group, switching re-
lays in said finders, a chain circuit extending through contacts on the switching re-
lays of a group, and a relay energized over 75 said chain responsive to an all finders busy condition in that group to remove battery from said distributor and place an artificial busy on the idle trunks terminating in that group.

80 15. In a telephone system, a subscriber's line terminating in individual lineswitches, a plurality of trunks outgoing from said lineswitches, plurality of groups of finder switches, one of said trunks terminating in 85 each of said finder switch groups, a distributor for each group including means for preselecting an idle finder of that group, means for operating one of said lineswitches to seize an idle trunk, a relay energized when 90 that trunk is seized to extend a start circuit towards a finder switch of that group, and means for completing said start circuit only if said distributor has completed the preselec-
95 tion of an idle finder.

16. In a telephone system, a plurality of groups of lineswitches, a plurality of groups of finder switches, outgoing trunks from each group of lineswitches, each group of lineswitches having a trunk terminating 100 separately in each group of finder switches and each group of finder switches terminat-
105 ing a trunk individual to each group of lineswitches, means for operating a lineswitch to seize an idle trunk accessible thereto, and means for starting an idle finder switch of the group in which the seized trunk terminates to find the seized trunk.

110 17. In a telephone system, a plurality of groups of lineswitches, a plurality of groups of finder switches, a plurality of groups of trunks, each group of trunks being associated with a group of lineswitches and having each of its trunks connecting that group of lineswitches to a different group 115 of finder switches and each group of finder switches terminating a trunk from each group of lineswitches, means for operating a lineswitch to seize an idle trunk accessible thereto, and means to start an idle finder switch of the group in which the seized trunk terminates to find the seized trunk.

120 In witness whereof, I hereunto subscribe my name this 30th day of July, A. D. 1925.

CLARENCE E. LOMAX.
